UNITED STATES PATENT OFFICE.

BENTON C. ROWELL, OF BOSTON, MASSACHUSETTS, ASSIGNOR TO THE
ROWELL AMERICAN SWITCH COMPANY, OF SAME PLACE.

CAR AND DEVICE FOR OPERATING AUTOMATIC RAILWAY-SWITCHES.

SPECIFICATION forming part of Letters Patent No. 434,889, dated August 19, 1890.

Application filed April 11, 1889. Serial No. 306,773. (No model.)

To all whom it may concern:

Be it known that I, BENTON C. ROWELL, of Boston, in the county of Suffolk and Commonwealth of Massachusetts, have invented 5
5 certain Improvements in the Devices Attached to Railway-Cars for Operating Automatic Switches, of which the following is a specification.

In railway-cars propelled by electricity the 10 space between the wheels thereof is occupied by the electrical motors and mechanism used in connection therewith to propel the cars, in consequence of which there is no available space upon the axles in which to apply devices for operating automatic switches, which 15 become a necessity when other means of propulsion than that of horse-power are used. My improvements, therefore, are most advantageous and especially applicable to cars propelled by electricity or other motive power than horses, although they may be used to great advantage in the latter case.

My invention consists in the improved construction of the switch-operating devices and 20 in attaching them to the axle-boxes of the car by means of a frame secured to the cups or bearings of the lower ends of the car-springs in a substantial manner, which frame also serves as a means for supporting a scraper, 25 plow, or fender in a position which will be constant with relation to the rails over which the car passes.

In the drawings forming a part of this specification, Figure 1 is a side elevation of a portion 30 of one end of a car, showing one wheel, the manner in which I attach to the axle-box the frame for holding a plow or fender, and the switch-operating arm, and the devices by which such arm is operated from the platform 35 at the end of the car, the platform being broken away; also an automatic switch mechanism in section beneath the car. Fig. 2 is a top view of the same portion of the car and the same devices, with a part of the bottom 40 of the car broken away. Fig. 3 is an end view of the same portion of the car and the same devices that are shown in Fig. 1.

Similar letters in the several figures indicate the same part of the contrivance.

50 A is the car-body; B, an axle-box; C, the frame on one side of the car attached to the

axle-box by means of hangers b, which support the switch-operating arms e e', as also a plow or fender D. The hangers b are attached to the cups or bearings c of the car-springs.

f f' are the levers which connect the arms e e' with the reciprocating sliding rods g g'. These rods are supported in guides h h', which are fastened to the car-body, and between them there is a slotted boss or enlargement i i' upon each rod, to which the levers f f' are pivoted. The space between the guides h h' should be just enough to allow the boss i i' to move a sufficient distance to carry the switch-operating arm from the position occupied by the one marked e' to that occupied by the one marked e. For the purpose of throwing the arms e e' down into the perpendicular position occupied by e, which is required to operate the switch, a chain or rope d, preferably of wire, is attached to the boss i or i' and passed around a grooved pulley k or k' in a block attached to the bottom of the car. Thence it is passed around another 75 grooved pulley l or l', near the end of the car, and thence to a hand-lever m or m', pivoted to the end or the dash-board of the car, as at n. When the hand-lever is up in the position of that marked m, the rod g will be pulled back until the boss i rests against the guide h', as shown, and this, through the rod f, will turn the arm e upon its pivot to the position shown in the drawings. When the hand-lever is thrown down into the position indicated by m' by means of a spring o acting upon the sliding rod, it will be drawn forward to the position illustrated by g', and thus, through the lever f', the switch-operating arm will be drawn into the position indicated by e'. 85

By attaching the ropes d to the hand-levers m m' a short distance from their pivotal point n, and providing a stop p, I have found that when the hand-lever is raised and pressed against the stop it will remain in that position without other means of holding it, for the reason that the point at which the rope is attached to the lever is carried past the center of the pivot n. It may be found desirable, however, to turn the ends of the cross-piece of the stop p inward a little, as at q, Fig. 2, so that they will bear against the hand- 90 95 100

lever when it is in an upright position, as illustrated by *m*.

In the drawings I have shown two switch-operating arms attached to the supporting-frame upon the same side of the car, by which means the switch can be turned in either direction, and if in making a "round trip" a car is turned end for end, as is often the case on street-railways, it will be necessary to have similar devices attached to the car upon the opposite side and at the other end thereof, and this also will be necessary if it is required to turn the car to the right when going in one direction and to the left when going in the other, or vice versa. I have also illustrated a convenient and comparatively inexpensive manner of attaching the supporting-frame C to the axle-boxes—that is, by extending the cups or car-spring sockets and bolting the hangers *b* thereto; but the hangers and cups may be cast in one piece.

The switch mechanism should be so arranged that when the driver or operator upon the car desires to set the switch so as to turn the car onto a track to the right he has only to raise the hand-lever at his right hand, which will throw the operating-arm *e* down into the position shown in the drawings, where it will depress the projecting switch-actuating plunger, as the car passes; and in the same manner the hand-lever at the left hand should be raised when it is desired to turn the car upon a left-hand track. The supporting-

frame C may also be utilized to carry a brush in front of the wheels to clear the track of snow or small obstructions.

The benefits of my improved construction are that it can be easily and economically applied to cars already built and without changing them in any manner, and also by attaching the said frame to the axle-boxes the plow, the rail-brushes, and the switch-operating arms all maintain a constant relation to the ground and rails, irrespective of the tilting of the car-body upon its springs.

I claim—

1. Devices for operating automatic switches from a railway-car, consisting of a switch-actuating arm pivoted to a support attached to its axle-box, a rod connecting said arm and a sliding rod held in guides upon the car, and a lever pivoted at the end of the car within control of the operator thereon, and a counter-acting spring, both connected with said rod to give it reciprocating motion, all combined in the manner substantially as described.

2. The combination of an automatic switch-operating device with a frame supported upon the axle-boxes of a railway-car by a rigid attachment to the car-spring bearings, substantially as described.

BENTON C. ROWELL.
